UNITED STATES PATENT OFFICE.

EDWARD T. ROBINSON, OF ST. LOUIS, MISSOURI, ASSIGNOR TO ST. LOUIS CAR COMPANY, OF ST. LOUIS, MISSOURI, A CORPORATION.

AUTOMOBILE-DOOR HINGE.

No. 878,745.

Specification of Letters Patent.

Patented Feb. 11, 1908.

Application filed July 29, 1907. Serial No. 386,024.

To all whom it may concern:

Be it known that I, EDWARD T. ROBINSON, a citizen of the United States of America, residing in the city of St. Louis and State of Missouri, have invented certain new and useful Improvements in Automobile-Door Hinges, of which the following is a full, clear, and exact description, reference being had to the accompanying drawings, forming part of this specification.

The object of my invention is to produce an improved door hinge for automobiles that will throw the door, when opening, well away from the body of the machine so that it will clear the wheel guards etc., thus allowing the door to be fully opened to permit free ingress and egress.

A further object of my invention is to produce a re-inforced hinge that will be strong and durable and form a perfect stop to the opening movement of the heavy doors of automobiles.

My invention consists in features of novelty hereinafter described and pointed out in the claims.

Figure I is a side view showing a door and part of the body of an automobile provided with my improved hinges. Fig. II is a vertical section taken on line II-II, Fig. I. Fig. III is a horizontal section taken on line III-III, Fig. I. Fig. IV is a detail horizontal section taken on line IV-IV, Fig. I. Fig. V is a perspective view of one of the hinges.

1 represents part of the body, and 2 one of the doors of an automobile.

3 represents the upper hinge, and 4 the lower hinge of the door. Each hinge consists of two metal members 5 and 6, the member 5 of each hinge being the one that is secured

to the body of the car and 6 the one that is secured to the door. The two members are connected together by a pin or pintle 7 passed through ears formed on the members.

Each member of each hinge is formed with a bend 8 so that its outer portion sets at an angle to its inner portion, as clearly shown in the drawings, and the body member of the hinge 4 is provided with a brace arm 9, and a brace rib 10, adapted to bear against the body, as shown in Fig. IV, to give strength and steadiness to the hinge, which necessarily has its pintle point some distance from the body owing to the usual swell in the formation of the body. The body member of each hinge is formed with reinforcing rib 11 having a shoulder 11^a and the door member of each hinge is provided with a re-inforcing rib 12 having a lip or projection 12^a. The lips 12^a are adapted to come against the shoulders 11^a and arrest the opening movement of the door and owing to the shape of the hinges the door is permitted to fully open before the lips impinge against the shoulders, as shown by dotted lines, Fig. III.

Claim:

A hinge for automobile doors, consisting of two members pivoted together and bent at an angle between their pivot and their point of attachment to the body and door of the car; the body member of the hinge being provided with a brace arm and a brace rib adapted to bear against the body of the car, substantially as and for the purpose set forth.

EDWARD T. ROBINSON.
